UNITED STATES PATENT OFFICE.

EDWARD JABANT, OF ST. ALBANS, VERMONT.

SCRUBBING-BRUSH HOLDER.

1,114,617.

Specification of Letters Patent.

Patented Oct. 20, 1914.

Application filed August 22, 1913. Serial No. 786,120.

To all whom it may concern:

Be it known that I, EDWARD JABANT, a citizen of the United States, resident of St. Albans, in the county of Franklin and State 5 of Vermont, have made a certain new and useful Invention in Scrubbing-Brush Holders; and I do declare the following to be a full, clear, and exact description of the same, such as will enable others skilled in 10 the art to which it appertains to make and use the invention, reference being had to the accompanying drawings, and to letters or figures of reference marked thereon, which form a part of this specification.

15 Figure 1 is a central longitudinal section of the invention as applied. Fig. 2 is a perspective view of the clamp portion. Fig. 3 is a detail perspective view of a modified form of the ferrule.

20 The object of the invention is to provide an improved holding attachment for scrubbing brushes, whereby it is designed to furnish means for using such a brush without soiling the hand.

25 The invention consists in the novel construction and combinations of parts, as hereinafter set forth.

In the accompanying drawings, illustrating the invention, the numeral 2, indicates 30 the holder or clamp; 3, a long handle, and 4, a scrubbing brush, to the middle of the body of which, the holder is designed to be connected.

The holder consists of a clamp portion 5, 35 and a tang 6, cut therefrom. The clamp portion 5, is of malleable plate iron, about one-eighth of an inch thick, and somewhat more than an inch wide. Its front end is provided with a downward extending flange 7, having points or teeth 8, directed inward 40 or backward to engage the body of the brush. Its rear end is provided with a downward turned flange 9, having a threaded aperture 10, for a thumb screw 12, designed to 45 engage the body of the brush in rear. A

tapered tang 6, formed from the body of the clamp, extends upward and backward obliquely at about an angle of sixty degrees, more or less.

A ferrule 14 has an oblique bottom having the same angular relation to its axis that the tang 6 has to the top of the clamp. It is designed to be fitted on the end of the handle 3, which is provided with a recess or kerf 15, to receive the tang 6, of the 50 holder clamp. This ferrule has an oblong slot in its bottom, of proper size to receive the tang, which is perforated at 16, just above the ferrule, for engagement with a short securing bolt 17, passing through the 55 handle. The ferrule engages by its oblique bottom the surface of the clamp protects the handle end and braces it as well as the tang and the short bolt 17 engaging the ferrule, the tang and the handle, holds the 60 parts securely together. This attachment is designed to fit scrubbing brushes of different sizes and is readily applied and removed. The ferrule is sometimes made with an open bottom, as shown in Fig. 3. 70

I claim:

A holder attachment for scrubbing brushes, comprising a flat-top brush-head clamp having an integral upturned and perforated oblique tang, a cleft and perforated handle 75 embracing said tang, an oblique ferrule upon the handle having a horizontal flat bottom provided with a central slot engaging the tang, said bottom bearing against the flat top of the clamp, and a securing bolt connecting the handle and the tang, whereby the flat bottom of the ferrule is braced and secured in bearing position against the flat top of the clamp.

In testimony whereof I affix my signature, 85 in presence of two witnesses.

EDWARD JABANT.
